UNITED STATES PATENT OFFICE.

RUSSELL H. BOWEN, OF PALMYRA, NEW JERSEY, ASSIGNOR TO THE AMERICAN PULLEY COMPANY, OF PHILADELPHIA, PENNSYLVANIA, A CORPORATION OF PENNSYLVANIA.

APPARATUS FOR CROWNING PULLEYS.

1,047,737.

Specification of Letters Patent. Patented Dec. 17, 1912.

Application filed July 20, 1910. Serial No. 572,808.

To all whom it may concern:

Be it known that I, RUSSELL H. BOWEN, of Palmyra, in the county of Burlington and State of New Jersey, have invented certain new and useful Improvements in Apparatus for Crowning Pulleys, whereof the following is a specification, reference being had to the accompanying drawings.

The object of my invention is to produce pulleys of sheet metal, such as steel, in which the otherwise flat rim is slightly beveled, on each side of the median plane of the pulley, the region of greatest diameter, toward which the beveled surfaces converge, being at or adjacent to said median plane.

As frequently constructed, the rim of a sheet metal pulley is built up from two flat annular bands of metal, arranged side by side and secured together around their adjacent edges, so as to present a practically true cylindrical surface on the exterior. The median plane above referred to, is that upon which the edges of these two flat bands meet. When the present invention is employed, the periphery of the finished pulley may be said to consist substantially of two frusta of cones, having slight pitch, and having their bases in juxtaposition at or near the median plane of the pulley structure.

In the accompanying drawings, I have shown an apparatus embodying my invention in a preferred form, and illustrated certain stages of its use in the manner preferred for carrying out the same. I have also shown a modified form of apparatus, which may be advantageously employed under certain circumstances, and in connection with these apparatus, I have shown a pulley whose rim structure is of the character above referred to, but it must be understood that such illustrations are to be taken as typical and not as restrictive.

In said drawings, Figure I, represents a horizontal sectional view of one form of press which may be employed in my process, showing in plan the upper side of the platen of said press, the plane of section being indicated at the line I, I, in Fig. II. Fig. II, is a view, partly in vertical central section and partly in side elevation, of said form of press, showing the parts in the initial position, corresponding to the commencement of the process. Fig. III, is a view partly in vertical section and partly in side elevation,

of the main elements of said form of press in the position corresponding to the completion of one stage of the process. Fig. IV, is a view in vertical central section of another form of press, intended to be employed when a single stage process is desired.

Referring to Fig. II, 1, indicates the pulley, in its initial condition and ready for the crowning process, the rim portions being indicated respectively at 2, and 3, and the median plane at 4. I preferably employ hydraulic pressure for effecting the necessary treatment, and in said drawings, 5, indicates the body portion of the movable platen of a hydraulic press adapted to be actuated by means of the plunger 6, operated in the ordinary manner from a hydraulic cylinder, which is not shown, as its construction and mode of operation are well understood. The stationary bed plate, or base 7, of the press structure, is mounted in any convenient manner, adapted to resist displacement. To said base is attached, by means of the rigid rods 8, the top plate 9, of the press, which receives the thrust of the platen transmitted through the pulley under treatment. Said base also carries a plurality of rigidly mounted upright posts 10, which may be of square cross-section arranged symmetrically with relation to the platen, in a manner which will be described later on. The body 5, of the platen is preferably hollow, and lens-shaped, as shown, having a plurality of slots 11, arranged at intervals corresponding with the positions of the posts 10, so as to permit the platen to clear said posts in its upward and downward movement. The platen also comprises the die-holding ring 12, of considerable vertical depth, said ring having its inner surface coned, or flared outwardly, upward, as indicated at 13. The ring is secured in position centrally upon the body 5, preferably by means of screws 14, passing through the flange 15, which projects radially outward around the base of the ring. Fitting snugly within the ring are the die segments 16, 17, 18, 19, 20, and 21, in this instance, six in number, whose outer surfaces are coned inwardly downward in correspondence with the coned surface 13, of the holding ring 12, while the inner surfaces of said segments are slightly coned or flared outwardly upward,

the pitch of said inner surfaces being that which is desired for the crowning or coning of the respective portions of the pulley's periphery, and being preferably less than the 5 pitch of the outer surfaces of the segments. The arcs of these segments together constitute substantially a complete circle, there being a comparatively slight interspace left between the proximate ends of each pair, 10 which interspace however, is of such a small extent as to be negligible in its effect upon the metal of the pulley, while yet preventing the segments from jamming too closely together under pressure. When arranged in 15 position within the holding ring 12, the die-segments form an internally coned annulus whose lower edge extends inward so as to overhang the tops of the posts 10, the joints between the respective pairs of segments being 20 preferably located in correspondence with said posts. The platen is also provided with auxiliary hydraulic cylinders 23, and 24, having plungers 25, and 26, respectively, which are adapted to depress the platen 25 after the cessation of its upward movement. The top plate 9, of the press may conveniently be formed with a central aperture 28, through which a suspension device, such as a rope 29, may pass in order to support 30 the pulley in position at the commencement of the operation. Such being the structure of the apparatus in this form, I will now proceed to describe the process which is conducted by means thereof. 35 The platen 5, being in its lower position, as shown in Fig. II, and the segments 16 to 21, inclusive, being arranged symmetrically within the holding ring 12, the pulley 1, is suspended co-axially with the said ring by 40 means of the rope, or other supporting device 29, and is held thereby against the under side of the top plate 9, so as to prevent accidental lateral displacement. Hydraulic pressure being then applied, the 45 platen moves upward and the lower edge of the pulley rim is received symmetrically within the upper extremity of the conical opening, formed by the combined die segments, the diameter of said opening corresponding substantially with the external diameter 50 of said edge. As the upward movement of the platen continues, the segments are forced over and upon the lower half of the pulley's periphery, bending and compressing the metal thereof radially inward, so that its external surface conforms in 55 pitch to the internal surface of the combined die segments. This upward movement continues until the top of the segmental die 60 reaches the median plane of the pulley, the position at this stage of the process being that shown in Fig. III. The hydraulic pressure upon the plunger 6, is then released and the plungers 25, and 26, are operated 65 to cause the descent of the platen, car-

rying with it the pulley, whose suspending device 29, is now temporarily released. As the downward movement of the platen continues, the lower surfaces of the die segments come into contact with the posts 10, 70 and the further continued movement forces the segmental die upward, with the lower half of the pulley in their embrace, so as to disengage the segmental die from the holding ring 12. This disengaging movement is 75 readily permitted by reason of the considerable flare or pitch of the external surfaces of the segments. As soon as the die segments have been raised a slight distance and are thus loosened, the pulley can be readily freed from them, and the operation of crowning the lower half of the pulley is now 80 complete. The pulley is then turned upside down, and the process is repeated upon the remaining half of the peripheral surface, 85 which is thus coned in symmetry with the other half, so that the result is to produce the desired crowning of the peripheral surface as a whole.

Referring now to Fig. IV, I have there 90 shown an apparatus which is adapted to permit the simultaneous crowning of both sides of the pulley rim, as distinguished from the successive operations above described. In said figure, 30, represents the 95 platen, and 31, the top plate of the press, having actuating and holding devices similar in general character to those just described. The platen 30, is provided with a die-holding ring and segmental dies, similar 100 in character to those above specified, (and which may conveniently be termed the lower die-holder, and lower segmental dies,) and the top plate is provided with a downwardly depending die-holding ring 32, 105 which I term the upper die-holder, and which is concentric with the lower die-holder. Within the upper die-holder 32, are arranged a plurality of upper die segments 33, similar in character and general 110 construction to those of the lower segmental die and retained elastically in position by means of downwardly depending rods 35, and springs 36, the tension of said springs holding the upper die segments in place 115 against the action of gravity. When this form of press is used, the pulley is centered and held as before stated, and upon the upward movement of the platen both the upper and lower dies are progressively forced upon 120 the rim in opposite directions, bending and compressing the metal thereof so as to crown both sides simultaneously. When the crowning operation is complete and the return movement of the platen takes place, the first 125 effect (due to the action of gravity) is to withdraw the upper segmental die from its seat within the upper die-holder, this action being permitted by the elastic retaining devices. As soon however, as the upper die 130

segments have been freed from the embrace of their holding element, they can readily be detached, or will detach themselves from the surface of the pulley rim, the lower die segments being freed from their holding element by contact with the posts as in the case first described.

Having thus described my invention, I wish it to be understood that various features of the apparatus above described are susceptible of modification without departing from the essential principle of construction and mode of operation characteristic thereof. Thus, for instance, I do not limit my claims to the use of any particular number of die segments, nor to the use of any particular means of affording the necessary pressure for the dies, nor to the exact arrangement of the coöperating moving elements whereby the pressure is applied.

I claim:—

1. In an apparatus comprising a platen, a top plate, and means for moving one of said elements with relation to the other, the combination of, a die-holding element, having a coned internal surface; and a plurality of die-segments having their external surfaces coned in conformity with the internal surface of the holding element, said die-segments having coned internal surfaces, and being adapted to form substantially a complete annulus, when arranged within said holding element.

2. In an apparatus comprising a platen, a top plate, and means for moving one of said elements with relation to the other, the combination of a die-holding element, having a coned internal surface; a plurality of die-segments having their external surfaces coned in conformity with the internal surface of the holding element, said die-segments having also coned internal surfaces; and means for freeing the dies from the

holding element upon the return movement of the pressing device.

45

3. In an apparatus comprising a platen, a top plate, and means for moving one of said elements with relation to the other, the combination of upper and lower die-holding elements, having coned internal surfaces 50 and respectively carried by said platen and said top plate; two sets of die-segments having coned internal surfaces and coned external surfaces and carried respectively by said die-holding elements; means for elastically retaining the die-segments in the upper die-holder; and means for freeing the lower die-segments, upon the return movement of the platen, substantially as set forth.

55

4. In a press provided with a suitable 60 source of power, the combination of a fixed base plate; upright posts arranged upon said base plate; a fixed top plate; a movable platen arranged between said base and said top plate; and slotted to permit movement 65 with relation to said posts; a holding element, carried by said platen, said holding ring having a flared internal surface; a plurality of die-segments having their external surfaces coned in conformity with 70 the internal surface of the holding element and having their internal surfaces also coned, the lower edges of said die being arranged in the described relation to said posts, whereby upon the return movement 75 of the platen, said die segments will engage with the upper extremities of the posts, substantially as and for the purpose set forth.

In testimony whereof, I have hereunto signed my name, at Philadelphia, Pennsylvania, this fifteenth day of July, 1910.

RUSSELL H. BOWEN.
